PRINTING PLATE WHIRLER

Fred A. Hacker, Cranford, N. J., assignor, by
mesne assignments, to American Type Found-
ers, Incorporated, Elizabeth, N. J., a corpora-
tion of New Jersey

Application August 3, 1944, Serial No. 547,851

3 Claims. (Cl. 91—42)

1

This invention relates to apparatus and equipment for preparing offset printing plates and for the effecting of associated operations in connection with photolithographic, duplicating, and similar processes.

The general object of the invention is to provide a novel and improved plate making machine of the class described which is of compact portable construction and which embodies various units of equipment needed to lay out, print, develop, rub-up and otherwise prepare offset or planographic plates for printing.

In its preferred embodiment, the invention contemplates the provision of a cabinet, preferably made of enameled sheet metal and having recesses or "pans" in its top, front and sides for the accommodation of the several adjustable and removable elements by which the various functions of the device are performed. When opened to its full dimensions for use, the machine occupies only about one-fourth of the floor space which would have been occupied by all of the separate units commonly employed in making offset plates, and when the cabinet is closed and the operative parts retracted or stowed within the cabinet, the device occupies no more space than a single piece of plate making equipment of average size. The novel offset plate making machine is consequently eminently suited for use in the field, in duplicating plants, in a truck, a trailer, or a plane, or on board ship.

The equipment included in the apparatus comprises a plate whirler, a light-top layout table, a vacuum printing frame, a printing lamp, a plate developing trough, a plate rubbing-up table and all of the necessary electrical connections and controls.

More specific objects of the invention include the provision of novel means for housing and supporting the novel plate whirler in cooperative relationship with the other various operative parts, and for enabling the whirler to perform its functions and to be used without interference with the others in spite of the compactness and accessibility of the arrangement.

The purpose and features of novelty of the invention will be more clearly understood from the following specification when read in conjunction with the accompanying drawings in which one embodiment of the invention is illustrated by way of example:

In the drawings:

Figure 1 is a plan view of a plate making machine embodying the principles of the invention; the printing frame; the light-top layout

2

table, and other accessories being in open or operative positions; and certain other portions of the device being broken away to reveal the construction of parts covered thereby.

Figure 2 is a view in front elevation of the machine shown in Figure 1;

Figure 3 is a vertical sectional view taken on line 3—3 of Figure 2; and

Figure 4 is a further enlarged view in vertical section showing the plate whirling mechanism and indicating the direction of air circulation.

By reference more particularly to Figures 1 and 2, of the drawings, it will be seen that the novel plate making machine comprises essentially a cabinet 10 by which the various operative members of the machine are supported and within which they may be snugly enclosed when the device is not in use, and for storage or transportation:

20 The cabinet 10 is provided with recesses or compartments at its top and sides for operative elements of the plate making machine while the front of the cabinet may be open to provide storage space for various accessory supplies and materials.

25 The central front compartment 12 of the cabinet is preferably provided with shelves 13 and is adapted to be closed by means of a detachable panel or door 15. In the embodiment illustrated, the door is provided with hinge projections or lugs 16 which fit into small holes in the threshold of the opening into the compartment 12. A latch 17, operable by the finger, is provided to retain the door or panel in place. When the plate making machine is in use, the door may be merely laid aside or stacked along with the other closure members against the wall.

30 Upon one side of the cabinet—the right hand side as viewed in Figures 1 and 2—a recess or compartment 18 is provided by a pan 19 which like the cabinet itself is preferably made of sheet metal. The pan 19 serves to receive the printing frame 20 when it is in stored or inoperative position or when it is disposed in a vertical position for horizontal printing.

35 Upon the opposite side of the cabinet a pan 21 defines a cavity or recess 22 which is adapted to receive the light-top table 25 when it is retracted. Both of the recesses 18 and 22 may be covered by a door or panel member similar to the front door 15.

40 Within the upper portion of the cabinet there is provided a space 27 the bottom of which is defined by the pan 28, the side walls 29 of the pan 55 being secured in suitable fashion to the walls 30

of the upper part of the cabinet. Access to the compartment or chamber 27 is had through an opening substantially co-extensive with the top of the cabinet. This opening is provided with a closure or lid 32. The lid or cover 32 is hinged to the upper portion of the rear side walls of the cabinet as at 33 and a knob or handle 34 is provided at the front edge of the cover for raising it. Supporting links 35 of the usual type are provided for maintaining the lid in upright open position.

The lid or cover 32 is primarily constructed of sheet metal but has secured to its sheet metal body portion, preferably by means of screws, a sheet of wood, Masonite, or other pressed wood or composition 36 which provides a rubbing-up surface for the plates.

The compartment or recess 27 is primarily intended to accommodate the plate whirler designated generally by the reference numeral 40. This whirler comprises a turntable 41 preferably constructed of a sheet metal plate secured to a supporting base or spider 42 having a central opening at 43 adapted to fit upon the top of the vertical shaft 45. Between the spider 42 and the turntable 41 there is preferably interposed a sheet of asbestos 46. An annular boss 47 is formed in the center of the spider and the walls of the boss are notched as at 48 to receive the cotter pin 49 carried by the shaft 45. The shaft is driven by the motor 50 which is suspended by means of the pan or drum 51 from the central portion of the bottom wall 28 of the whirler compartment. The vertical shaft 45 may be pinned or otherwise secured to the motor shaft 53 as indicated at 54 in Figure 6 of the drawings. Secured to the drum 51, as by means of the bolts 56, is the electrical resistance heating annulus 57. An annular series of openings 58 is formed in the bottom of the pan or drum 51 for the admission of air which is heated by the heating element 57 and then passes through the opening 60 in the pan 28, whereupon the blades or flanges 61 secured to the underside of the turntable 41 serve to circulate the air through the compartment 27 and around the plate carried by the turntable 41 and thence out through the louvers 62 in the rear wall 30 of the cabinet.

A sheet of asbestos material 63 serves to protect the margins of the opening 60 in the pan 28 and a vertically disposed cylinder 64 of asbestos coated material protects the driving shaft 45 from the hot air.

The means just described provide a very efficient device for evenly coating and drying the photolithographic plates, and one which occupies a minimum of space within the cabinet, affording ample room for other elements of the combination machine.

There may be arranged for disposal immediately above the whirler within the upper portion of the recess or compartment 27, the sheet-metal developing trough 65. The developing trough consists essentially of a rectangular pan let into the top opening of the cabinet and hinged to the upper edge of the rear wall thereof. The hinge arrangement consists of the horizontal rod 66 secured by means of the ears 67 to the rear margin of the trough and this rod or bar 66 is received for rotation within angled notches in the brackets 69 carried by the cabinet in the margins of the top opening therein.

The side and front marginal flanges of the trough 65 are provided with handles 70 by means of which it may be tilted around its hinge sup-

ports or entirely removed from the cabinet. In order to retain the trough 65 in its tilted position to provide access to the plate whirler, pivoted bracing links or the like may be provided.

The bottom wall 80 of the trough 65 slopes rearwardly and laterally toward the right hand rear corner of the trough where there is provided a down-spout 82 which in normal position registers with the elbow 83 which extends between the bottom of the pan 28 and the rear wall 30 of the cabinet, which elbow 83 also provides a drain for the whirler compartment for enabling the compartment or enclosure to be cleaned or flushed when necessary. Any suitable flexible or detachable drain connection may be applied to the discharge end 84 of this elbow.

Within the developing trough 65 there may be disposed a wooden slatted drain rack 85 the rear edge of which rests upon the supporting angle piece 86 secured to the rear wall of the trough and the forward edge of which is latched in its lowermost position by means of the spring catch 87 having the projected button 88 thereon.

At the upper rear portion of the developing trough 65 is provided a narrow tray 89.

It will be understood that various changes and modifications may be made in the embodiment illustrated and described herein without departing from the scope of the invention as defined by the following claims.

Having thus described the invention what is claimed as new and desired to be secured by Letters Patent is:

1. Apparatus for making photolithographic printing plates and the like, which comprises a cabinet having a compartment therein, a horizontal rotary plate whirler mounted on the bottom of said compartment, a motor for driving said whirler, an electrical heating element below the plane of said whirler and within the lateral confines thereof, air inlet openings in the bottom of said compartment adjacent said heating element, fan blades on the lower surface of said whirler for circulating the air, and air outlet openings in said cabinet above the plane of the whirler.

2. In a plate making machine, a plate whirler compartment, an opening in the bottom wall of said compartment, a pan-like supporting bracket secured to said bottom wall and extending below said opening, a motor carried by said bracket and having a shaft extending vertically through the opening, a turntable on said shaft within said compartment, a heating element within said pan-shaped bracket below said opening, and a plurality of openings in the bottom of said pan-shaped bracket whereby air may pass through said openings around said heating element, thence through the opening in the bottom wall of said compartment and around the turntable.

3. In a plate making machine, a plate whirler compartment, an opening in the bottom wall of said compartment, a pan-like supporting bracket secured to said bottom wall and extending below said opening, a motor carried by said bracket and having a shaft extending vertically through the opening, a turntable on said shaft within said compartment, a heating element within said pan-shaped bracket below said opening, a plurality of openings in the bottom of said pan-shaped bracket whereby air may pass through said openings around said heating element, thence through the opening in the bottom wall of said compartment and around the turntable,

and fan blades secured to the underside of said turntable to circulate the air.
